ROOF CONSTRUCTION FOR TRACTION LOCOMOTIVES

Filed Dec. 19, 1929

Fig.1

A technical line drawing of a building facade. The upper portion features three sections of vertical slats, each with a horizontal band of windows. The left section has labels f^3 , d^1 , d^2 , f^5 , e^1 , d^1 , d^2 , b , f^5 , e^1 , d^1 , d^2 , and f^3 . The middle section has labels f^4 and f^4 . The right section has labels d^2 , d^1 , d^1 , d^2 , and f^3 . The base of the building has a row of windows with labels f^1 , f^2 , f^2 , f^1 , a , e^1 , d^1 , a , and b .

ROOF CONSTRUCTION FOR TRACTION LOCOMOTIVES

Application filed December 19, 1929. Serial No. 415,266.

The present invention relates to rail car constructions and embodies, more specifically, an improved roof construction for traction locomotives, the locomotive cooling units being conveniently embodied in the roof structure to provide effective cooling thereof, at the same time maintaining them in such position that they will not obstruct the convenient operation of the locomotive.

10 The present invention contemplates mounting the cooling units in the above manner, not only to effect the above results, but afford maximum protection for the units as well as simplicity of the locomotive cooling system.

An object of the invention, therefore, is to provide an improved roof construction for traction locomotives in which is embodied the cooling units thereof.

20 A further object of the invention is to provide a roof construction of the above character in which a false roof is provided including the cooling units, sufficient space being maintained between the false and true roofs to insure the necessary flow of cooling air through the units.

Further objects, not specifically enumerated above, will be apparent as the invention is described in greater detail in connection with the accompanying drawings, wherein:

30 Figure 1 is a plan view, partly broken away, showing a locomotive roof constructed in accordance with the present invention.

35 Figure 2 is a view in side elevation, showing the roof construction of Figure 1.

Figure 3 is a view in end elevation showing the foregoing roof construction.

40 Referring to the above drawings, *a* designates the sides of a locomotive cab provided with exhaust stacks *b*. In the present construction, three such stacks have been shown, but it will be readily apparent that this number may be varied in accordance with the 45 type of locomotive and specific construction thereof. A roof *c* is formed on the cab, the exhaust stacks extending therethrough as clearly shown in Figure 3.

The cooling units for the locomotive are 50 radiators of usual construction and are indi-

cated at *d*, the radiators including upper and lower headers *d'* and *d''*, respectively. Lower headers *d''* are securely mounted upon the roof *c* to prevent relative movement between such portions of the radiators and the roof. These headers are adjacent the sides of the cab and the radiators thus extend upwardly and inwardly to afford the desired sloping as shown in Figure 3. The upper headers *d'* are mounted upon expansion plates *e* which permit relative movement between the headers *d'* and roof *c*, thus providing for expansion of the radiators in operation.

About these radiators which are spaced upon either side of the roof and extend along the length thereof, a false roof *f* is mounted. The false roof is formed with eaves *f'* which may be secured to the sides of the cab, drip plates *f''* being provided. At either end of the roof, the false roof sections are secured to the end stacks *b* as at *f''*. The false roof sections *f* are mounted in pairs upon the roof of the cab and thus extend from a vertical longitudinal plane adjacent the median plane of the cab to the sides thereof, leaving a space between the adjacent edges of the sections sufficient to receive the exhaust stacks and other cooling mechanism, such as expansion tanks, etc. Within the false roof sections *f*, apertures *f''* are formed, these apertures being of a size sufficient to receive the radiator sections *d* therein. The portions of the false roof *f* between adjacent radiators are mounted at their upper extremities upon expansion plates *e'* which are independent of the expansion plates *e*.

From the foregoing, it will be seen that the false roof construction directs the flow of cooling air through the radiator sections and prevents any flow in a vertical direction through the false roof without passing through such sections. The roof is of such character that it may be readily mounted and dismounted from the cab, at the same time affording adequate protection for the units and being of such character that it will withstand the stresses and strains incident to operation of the locomotive.

While the invention has been described

with specific reference to the accompanying drawings, it is not to be limited, save as defined in the appended claims.

We claim as our invention:

- 5 1. A vehicle roof construction comprising a plurality of radiators upon opposite sides of the vehicle, means to mount the radiators upon a permanent vehicle roof, a plurality of exhaust stacks, a false roof formed of two sections spaced apart along the central portion of the roof, means to mount the sections on the stacks, means to secure the false roof to the sides of the permanent roof, and means to mount the portions of the false roof between the radiators to the permanent roof with provision for relative movement with respect thereto. 70

10 2. A vehicle roof construction comprising a plurality of radiators upon opposite sides of the vehicle, means to mount the radiators upon a permanent vehicle roof, a plurality of exhaust stacks, a false roof formed of two sections, means to mount the sections on the stacks, means to secure the false roof to the sides of the permanent roof, and means to mount the portions of the false roof between the radiators to the permanent roof with provision for relative movement with respect thereto. 75

15 3. A vehicle roof construction comprising a plurality of radiators upon opposite sides of the vehicle, means to mount the radiators upon a permanent vehicle roof, a plurality of exhaust stacks, a false roof, means to mount the false roof on the stacks, means to secure the false roof to the sides of the permanent roof, and means to mount the portions of the false roof between the radiators to the permanent roof with provision for relative movement with respect thereto. 80

20 4. A vehicle roof construction comprising a plurality of radiators upon opposite sides of the vehicle, means to mount the radiators upon a permanent vehicle roof, a plurality of exhaust stacks carried by the roof, a false roof, apertures in the false roof to receive the radiators, means to secure the false roof to the stacks, means to secure portions of the false roof between the radiators to the permanent roof with provision for relative movement with respect thereto, and means to secure the false roof to the sides of the permanent roof. 85

25 5. A vehicle roof construction comprising a plurality of radiators, means to mount the radiators upon a permanent vehicle roof, a plurality of exhaust stacks carried by the roof, a false roof, apertures in the false roof to receive the radiators, means to secure the false roof to the stacks, means to secure portions of the false roof to the permanent roof with provision for relative movement with respect thereto, and means to secure the false roof to the sides of the permanent roof. 90

30 6. A vehicle roof construction comprising a plurality of radiators upon opposite sides of the vehicle, means to mount the radiators upon a permanent vehicle roof, a plurality of exhaust stacks, a false roof formed of two sections spaced apart along the central portion of the roof, means to mount the sections on the stacks, means to secure the false roof to the sides of the permanent roof, and means to mount the portions of the false roof between the radiators to the permanent roof with provision for relative movement with respect thereto. 95

35 7. A vehicle roof construction comprising a radiator, means to anchor one end of the radiator to a permanent roof of the vehicle, means to mount the other end of the radiator with provision for movement relative to the permanent roof, an exhaust stack, a false roof, means to secure a portion of the roof to the stack, means to secure a portion thereof to the top with provision for relative movement with respect thereto, and means to secure the false roof to the sides of the permanent roof, said false roof having an aperture to receive the radiator. 100

40 8. A vehicle roof construction comprising a radiator, means to anchor one end of the radiator to a permanent roof of the vehicle, means to mount the other end of the radiator with provision for movement relative to the permanent roof, an exhaust stack, and a false roof secured to the stack and to a side of the vehicle top, the portion of the false roof adjacent the sides being curved outwardly and downwardly. 105

45 9. A vehicle roof construction, comprising a radiator, means to anchor one end of the radiator to a permanent roof of the vehicle, means to mount the other end of the radiator with provision for movement relative to the permanent roof, an exhaust stack, and a false roof secured to the stack and to a side of the vehicle top. 110

50 10. A vehicle roof construction, comprising a radiator, means to anchor one end of the radiator to a permanent roof of the vehicle, means to mount the other end of the radiator with provision for movement relative to the permanent roof, and a false roof surrounding the radiator. 115

55 This specification signed this 13th day of December, A. D. 1929.
